UNITED STATES PATENT OFFICE.

ARTHUR G. MCKEE, OF CLEVELAND, OHIO.

DISTRIBUTOR-DRIVING MECHANISM FOR BLAST-FURNACE STACKS.

Application filed April 25, 1925. Serial No. 25,892.

The present invention has to do with the mounting of the upper hopper or distributor and to the means provided for rotating the same where, as in approved modern practice in charging blast furnaces, two superposed hoppers are provided at the top of the furnace stack, the upper hopper being rotatably supported on the lower and larger hopper in order to facilitate the uniform distribution of the various materials which are initially received in such upper hopper. The general arrangement of hoppers just referred to will be found fully set forth in my prior U. S. Patents No. 864,795, dated September 3, 1907, and No. 890,569, dated June 9, 1908, and in certain respects the present construction may be regarded as a modification or improvement of that which forms the subject-matter of my pending application filed October 9, 1924, Serial No. 742,523.

As in such pending application, the principal object of the present invention is to provide a motor drive which is mounted integrally upon the distributor, thus eliminating any form of extraneous drive.

As built heretofore the blast furnace distributor has had its driving mechanism partly supported on the distributor itself and partly on the gas seal of the furnace or on the platform of the furnace, both of which are separate from the distributor and likely to shift in their relation thereto, from time to time, due to the expansion and contraction of the several parts and to the possible warping of the supporting structures. This puts the drive out of line and causes serious trouble and likely protracted stoppage for repairs.

It is moreover necessary, from time to time, to dismantle the distributor, removing it from its operating location so as to make it possible to replace the blast furnace bell or hopper or other equipment. Such dismantling and reassembling should, of course, be done as rapidly as possible so that the interruption to the operation of the blast furnace incident thereto be as short as possible. With the device as heretofore built the dismantling has made it necessary to take the distributor drive apart and then, when it was reassembled it was necessary to carefully adjust and re-align its several parts so that they would operate efficiently. All of this, as required, made a considerable loss of time and money.

In my invention I have provided an entire drive, including the motor, integral with half of the spider supporting the ball race and distributor thereon. This drive is assembled in the shop where manufactured, is shipped integrally with the spider referred to, without removing any of its parts, and during operation it is held rigidly with all of its parts in proper relation to each other. In case of dismantling the furnace top for replacement of a bell, or otherwise, the spider casting and the drive are removed and set aside as one piece and when reassembled are merely set back in place without disturbing the inter-relation of its several parts. With this arrangement all mechanism is taken off the platform of the furnace stack as is highly desirable and the operation of the furnace as a whole is simplified and rendered more convenient.

A further object of the invention is to provide an improved form of gas seal between such distributor and the stationary hopper on which it is thus supported.

To the accomplishment of the foregoing and related ends, the invention, then, consists of the means hereinafter fully described and particularly pointed out in the claims, the annexed drawing and the following description setting forth in detail certain mechanism embodying the invention, such disclosed means constituting, however, but one of various mechanical forms in which the principle of the invention may be used.

In said annexed drawing:—

Fig. 1 is a plan view of a furnace stack equipped with my improved distributor drive; Fig. 2 is a broken side elevation thereof; Fig. 3 is a vertical section taken on the plane indicated by the line 3—3, Fig. 1; and Fig. 4 is a section on the same plane as Fig. 3, but showing a modification in one detail.

In the drawing, only the upper wall 1 of the cover or cap called the gas seal for the lowermost of the two hoppers provided at the top of the furnace stack is shown, such wall being of frusto-conical form and suitably supported on the upper end of the furnace shaft (not shown). Mounted in turn on such cap is a cylindrical shell 2 that constitutes the body of the second hopper or distributor. As previously indicated, such distributor requires to be rotatably supported; in fact it derives its name from this circumstance. The main elements of such ro-

110

tatable mounting are a base in the form of a spider ring casting 3 that is removably supported on the flanged neck 4 that surmounts cap 1; an annular ball race 5 that is in turn supported on the upper face of said spider ring casting; and a complementary ball race 6 that is bolted to a laterally projecting flange 7 on the distributor 2. The balls 8 interposed between the races 5 and 6, it will thus be seen, serve rotatably to support said distributor on the upper end of cap 1. The lower ball race 5 is provided with downwardly opening apertures 9 at spaced intervals to permit the escape of dust or like matter from such race.

The spider ring 3, it will be noted, is formed with an inwardly and upwardly inclining flange 10 that overlies a flange 11 that projects outwardly from the hopper 12 of the distributor and has a face of complementary beveled form. Only enough clearance is left between the two flanges to permit of the free rotation of the distributor.

A special gas seal ring 13 made up of segments suitably bolted together, surrounds the hopper 12 in the space between the flange 7 thereon and the inwardly directed flange 10 on the spider ring 3, such seal ring being laid loosely upon the upper surface of said flange and having a close moving fit around the outside of rotating hopper 12.

It is necessary, of course, that flange 10 on the spider ring should have sufficient clearance between it and the hopper, so that they will never come into contact with each other, due to eccentricity of the two circles, or any other cause, and thus cause friction. However, such a clearance would permit too much gas to escape, if this opening were not sealed more tightly, and so for this purpose the seal ring 13 is provided in supplement to the seal provided by flanges 10 and 11. As just indicated said ring 13 is made to fit easily around the hopper and with sufficient clearance so that the hopper may revolve without dragging the ring with it. By this provision, after the distributor is erected, regardless of whether the hopper is exactly concentric with the spider, the seal ring automatically centers itself with the center of rotation of the hopper, and so long as the seal ring is actually larger than the hopper the latter can revolve freely, and in case the hopper shifts laterally, the ring will be moved thereby to a new location concentric with the new position of the hopper and the seal will thus be permanently maintained without possibility of frictional resistance to the rotation of the hopper.

It will thus be seen that whether, due to lateral mal-adjustment of the hopper with respect to the spider, or to the lowering of the hopper due to wearing of the ball races or balls, or for other cause, the seal ring

automatically is shifted to maintain the proper seal against the escape of gas.

In order to further increase the resistance to the movement of gas through the opening between the seal ring and the hopper, I may also cut grooves or rabbets in the vertical surface of the ring, or the outer surface of the hopper, or both. Thus as shown in Fig. 4, one such modified form of seal ring 14 is shown, such ring having a rabbet 14^a on its inner face and the hopper 12 having a complementary rib 14^b on its outer face, so that the escape of gases between the two surfaces is still more effectively hindered.

The upper ball race 6 is formed about its entire circumference with gear teeth 15 that constitute thereof an annular rack and the drive mechanism of interest in the present connection co-operates with such rack to rotate the distributor 2 in desired manner. This drive mechanism comprises in effect two separate units, viz., an electric motor 17 and a worm reduction gear 18. Said motor is of standard construction and is bolted directly to a depending bracket support 19 formed integral with the spider ring casting at one point, while the worm reduction gear is attached to a similar depending bracket support 20 at another point on said ring. The outwardly directed faces of the supports 19 and 20, to which the motor and worm gear reduction are thus attached, are not only separate but need not lie in the same plane in view of the fact that the casing of the worm gear reduction, as shown in Fig. 1, is so formed as to present the axis of the worm 21 that constitutes the drive element of said gear in proper alignment with the motor spindle 22, a flexible coupling 23 being utilized to connect such spindle to the projecting end of the worm.

The worm gear 24 that meshes with worm 21 is fixed to a vertical spindle 25 that is journaled intermediately of its ends in a bearing 26 formed directly in the housing that encloses said worm and gear, the upper end of said spindle lying alongside the rack 15 and being provided with a spur pinion 27 that meshes with said rack.

With the arrangement as set forth above, it is possible to support the vertical shaft carrying the spur pinion 27 and the worm wheel 24 for its entire length and also to provide suitable thrust and step bearings. As built heretofore this vertical shaft had to be supported at the middle with the driving gears overhung at each end, making a very difficult arrangement to maintain in alignment.

A suitable brake 30 is associated with the motor, while a limit switch 31 of standard design is mounted on the gear casing so as to be driven from spindle 25, such switch being arranged to stop rotation of the annular rack 15 at predetermined intervals.

From the foregoing description it will be seen that in addition to incorporating an improved form of gas seal, which obviates the difficulty encountered in prevailing designs 5 that as the ball bearing which supports the distributor becomes worn frictional engagement between the flanges that form such seal will result, I provide an extremely simple and compact driving mechanism for said distributor, the efficiency of which will be 10 permanently maintained as its several parts are rigidly held in proper relation to each other with a permanent oil bath providing proper lubrication and from the time when 15 manufactured and assembled in the shop there should be no necessity for disturbing the driving mechanism in the relation of its several parts to each other for a period of many years, thus making a marked improvement 20 over any equipment heretofore contemplated. In addition not only may a standard motor be used but this may be attached to the depending bracket 19 without any 25 change in its casing or base, the latter being bolted directly against such bracket.

Other modes of applying the principle of my invention may be employed instead of the one explained, change being made as regards the mechanism herein disclosed, provided the means stated by any of the following 30 claims or the equivalent of such stated means be employed.

I therefore particularly point out and distinctly claim as my invention:—

35 1. In blast furnace charging mechanism, the combination of a rotary distributor; a base ring providing an annular bearing for said distributor; integral brackets depending from said ring and presenting vertical 40 clamping faces; a motor mounted on one such face; and a reduction gear mounted on the other such face, said gear being coupled to said motor and having driving connection with said distributor.

45 2. In blast furnace charging mechanism, the combination of a rotary distributor; a base ring providing an annular bearing for said distributor; integral brackets depending from said ring and presenting vertical 50 clamping faces; a motor mounted on one such face; a reduction gear mounted in the other such face, said gear being coupled to said motor and having driving connection with said distributor; and co-operative gas sealing flanges on said spider ring and distributor, said flanges being free to move apart upon wear of the bearings between 55 said ring and distributor.

60 3. In blast furnace charging mechanism, the combination of a rotary distributor; a base ring providing an annular bearing for said distributor; integral brackets depending from said ring and presenting vertical 65 clamping faces; a motor mounted on one such face; a reduction gear mounted in the

other such face, said gear being coupled to said motor and having driving connection with said distributor; and complementary beveled gas sealing flanges on said spider ring and distributor, said flanges being free 70 to move apart upon wear of the bearings between said ring and distributor.

4. In blast furnace charging mechanism, the combination of a rotary distributor; a base ring providing an annular bearing for 75 said distributor; integral brackets depending from said ring and presenting vertical clamping faces; a motor mounted on one such face; a reduction gear mounted on the other such face, said gear being coupled to 80 said motor and having driving connection with said distributor; an inwardly directed annular flange on said spider ring, the under side of said flange being beveled downwardly and outwardly; and an outwardly 85 directed flange on said distributor lying beneath said first-named flange and having a complementary beveled face, whereby a gas seal is formed between said spider ring and distributor, said flanges being free to move 90 apart upon wear of the bearings between said ring and distributor.

5. In blast furnace charging mechanism, the combination of a rotary distributor; a base ring providing an annular bearing for 95 said distributor; integral brackets depending from said ring and presenting vertical clamping faces; integral brackets depending from the latter and presenting vertical 100 clamping faces; a motor mounted on one such face; a reduction gear mounted on the other such face, said gear being coupled to said motor and having driving connection with said distributor; and inwardly directed annular flange on said spider ring, the under side of said flange being beveled downwardly and outwardly; an outwardly directed flange on said distributor lying beneath said first-named flange and having a complementary beveled face, whereby a gas 110 seal is formed between said spider ring and distributor, said flanges being free to move apart upon wear of the bearings between said ring and distributor; and a supplemental seal ring loosely supported on said first- 115 named flange and having its inner face closely parallel to the adjacent wall of said hopper.

6. In blast-furnace charging mechanism, the combination with the stationary hopper; of a ring surmounting said hopper, a distributing hopper rotatably supported on said ring; and gas-sealing means comprising co-operative gas-sealing flanges on said ring and distributing hopper, said flanges being 120 free to move compensatively upon wear of the bearings between said ring and hopper.

7. In blast-furnace charging mechanism, the combination with the stationary hopper; of a ring surmounting said hopper, a dis- 130

- tributing hopper rotatably supported on said ring; and gas-sealing means comprising complementary bevelled gas-sealing flanges on said ring and distributing hopper, said flanges being free to move compensatively upon wear of the bearings between said ring and hopper.
8. In blast furnace charging mechanism, the combination with the stationary hopper; 10 of a spider ring surmounting said hopper, a distributing hopper rotatively supported on said spider ring; an outwardly directed annular flange on said spider ring, the under side of said flange being beveled downwardly and outwardly; an outwardly directed flange on said distributing hopper lying beneath said first-named flange and having a complementary beveled face, whereby a gas seal is 40 formed between said spider ring and distributing hopper, said flanges being free to move apart upon wear of the bearings between said ring and hopper; and a supplemental seal ring loosely supported on said 45 first-named flange and having its inner face closely parallel to the adjacent wall of said hopper.
9. In blast furnace charging mechanism, the combination with the stationary hopper; 25 of a base ring surrounding said hopper; a revolving hopper rotatively supported on said base ring; and a self centering seal ring, resting on such base ring and having a close moving fit with the hopper.
- 30 10. In blast furnace charging mechanism, the combination with the stationary hopper; of a spider ring surmounting said hopper, a distributing hopper rotatively supported on said spider ring; an outwardly directed annular flange on said spider ring, the under side of said flange being beveled downwardly and outwardly; an outwardly directed flange on said distributing hopper lying beneath said first-named flange and having a complementary beveled face, whereby a gas seal is 40 formed between said spider ring and distributing hopper, said flanges being free to move apart upon wear of the bearings between said ring and hopper; and a supplemental seal ring loosely supported on said 45 first-named flange and having its inner face closely parallel to the adjacent wall of said hopper.
11. In blast furnace charging mechanism, the combination with the stationary hopper; 50 of a spider ring surmounting said hopper, a distributing hopper rotatively supported on said spider ring; co-operative gas sealing flanges on said spider ring and distributing hopper, said flanges being free to move apart upon wear of the bearings between said ring and hopper; and a supplemental seal ring loosely supported on the upper of said flanges and having its inner face closely 55 parallel to the adjacent wall of said hopper.

Signed by me, this 13th day of April, 1925.

ARTHUR G. McKEE.
